MANUAL RESET VALVE

Eugene Paille, Los Angeles, Calif., assignor to
 General Controls Co., Glendale, Calif., a corpora-
 tion of California

Application April 18, 1942, Serial No. 439,493

5 Claims. (Cl. 137—139)

My present invention relates to fluid control valves, and particularly to those of the manual-reset type wherein a closure member, normally biased to closed position, is brought to open position by manual means, in which open position it is retained by means responsive to a controlling condition.

Manual-reset valves of the type indicated have particular utility for the control of fluid fuel supply to a burner, means responsive to the flame of the burner then being provided for controlling the means by which the valve is maintained in open position. Such means may consist of a thermostatic device for actuating a latch mechanism; or, more commonly, a thermoelectric generator or thermal cut-out may be employed for controlling the energization of electromagnetic holding means. In any event, upon extinction of the burner flame, the holding means become ineffective and the valve closes, manual resetting of the valve then being required for subsequent operation of the burner.

In a burner control system, wherein the manual-reset valve is employed for controlling fuel supply to a main burner, for the ignition of which a normally constantly-burning pilot burner is provided, it is desirable to provide means, effective during the resetting operation, to prevent the possibility of unignited gas being passed to the main burner while the pilot burner is extinguished. With this idea in mind, it has been proposed that the closure member remain in its closed position during the resetting operation until the condition responsive holding means is effective, when, upon completion of the resetting cycle, the closure member can reassume its open position. This invention concerns an improved form of such a device.

An object of this invention is to provide, in a valve of the type indicated, a manually-controlled fluid-pressure-motor for operating the reset mechanism while simultaneously holding the closure member on its seat.

Another object is to provide, in a valve of the type indicated, a resetting means that can be manually controlled or operated from a point remote from the valve.

Other objects and advantages of my invention will be found in the description, the drawing, and the appended claims; and for complete understanding of the invention, reference may be had to the following detailed description and accompanying drawing, wherein:

Figure 1 is a sectional view of a manual-reset valve embodying my invention;

Figures 2 and 3 are fragmentary views, mainly in section, of the valve shown in Fig. 1, the parts being shown in different positions assumed in operation; and

Figures 4 and 5 are views of modified forms of pressure generating means.

In the drawing, the numeral 11 indicates a valve casing having an inlet 12 and an outlet 13 separated by a partition 14 having an opening 15 therethrough, the upper end of the wall of the opening providing an annular valve seat 16. Closing an opening in the upper wall of the casing 11, and secured at its margin between the casing and the flanged lower end of a housing 18 bolted thereto, is a flexible diaphragm 17; a screened opening 19 is provided in the diaphragm for the equalization of fluid pressures on the opposite sides thereof. Secured centrally to the underside of the diaphragm 17, and guided thereby, is a metallic closure member 20 provided with an annular fibrous insert 21 cooperable with the seat 16. The closure member is constantly urged away from the seat 16 by a helical spring 22 compressed between the underside of the closure member and the lower wall of the casing. Centrally mounted on the upper side of the diaphragm 17 is a fluid pressure motor, generally indicated at 25, comprising an expansible-contractible metallic bellows 26 having upper and lower end-walls 27 and 28, respectively, which are joined to the bellows as by solder. The motor 25 is secured to the diaphragm 17, as is also the closure member 20, by a bolt 29.

Mounted on the underside of the top wall of the housing 18 is an electromagnet 30 comprising a U-shaped core 31, about one leg of which is wound an energizing coil 32; lead wires 33 connect the coil with terminals 34, insulatingly mounted in the side wall of the housing. The electromagnet is conveniently energized by a thermoelectric generator 37 adapted to be heated by a pilot burner flame 38, the generator being connected to the terminals 34 by wires 40. The upper end-wall 27 of the motor 25 is of magnetic material and serves as an armature adapted to be magnetically held by the core 31 when brought into engagement therewith by mechanical means.

Extending into an opening through the top wall of the casing 18 and the base of the core 31 is a metal tube 41, which carries at its free end a manually operable air pump 42 comprising a cylinder 43 and a piston 44 for which an operating stem 45 is provided. The inner end of the tube 41 is fluidly connected with the bellows chamber 46 by a second bellows 47 and an opening 48 ex-

tending through the upper end-wall 27 of the motor. The bellows 47 serves only as a yieldable fluid conductor and is joined, as by solder, at one of its ends to the top surface of the end-wall 27 and at its other end to the underside of the base of the core 31. The pump 42 is adapted, upon movement of the piston in one direction, to increase the fluid pressure in the bellows chamber 46, and upon reverse movement of the piston to relieve this pressure. Compressed between the core 31 and the end-wall 27, and encircling the bellows 47, is a helical spring 49. The force of this spring is transmitted to the closure member 20 through a pair of rods 50 carried by the upper end-wall 27 of the motor. The force of spring 49 is considerably greater than that of the opposing spring 22.

The operation of the valve is as follows: assuming the parts to be in the positions shown in Fig. 1, the closure member 20 is held on its seat 16 by the force of spring 49 (and pressure of fluid at inlet of valve) against the opposing force of spring 22; and the electromagnet core 31 is energized by current from the thermoelectric generator 37, the pilot burner flame 38 being alight. If the pump 42 is now operated to increase the pressure in the bellows chamber 46, this pressure will act downwardly on the lower end-wall 28 to hold the closure member 20 on its seat, and simultaneously exert a force to move the armature, or upper end-wall 27, into engagement with the pole faces of the core 31. Upon such engagement, the upper end-wall will be magnetically held, and the spring 49 will therefore no longer exert a force on the closure member 20, the same being held on its seat by the fluid pressure in the motor; the parts now being in the positions shown in Fig. 2. If the pump 42 is now operated to relieve the fluid pressure in the bellows chamber 46, closure member 20 will be moved away from its seat 16 by the force of spring 22, and assume its operated, or open, position as shown in Fig. 3. Should the pilot burner flame become extinguished, upon resultant cessation of current generation by the device 37, the electromagnet will be deenergized, thus permitting the upper end-wall 27 to move downwardly under the force of spring 49, which, when the rods 50 engage the lower end-wall 28, will exert a downward force on the closure member and move the same to its closed position against the force of spring 22; the parts reassuming the positions shown in Fig. 1. Relighting of the pilot flame is, of course, necessary before the closure member can again be opened.

In Figs. 4 and 5 are shown modifications of the means for varying the fluid pressure in the bellows chamber 46. The bulb 51 of Fig. 4 is filled with fluid and is made of flexible material, such as rubber, so that the fluid can be forced from the same through the tube 41, and into the bellows chamber by manual operation. In Fig. 5, the numeral 52 indicates an expansion bulb adapted to be heated by an auxiliary burner flame 53 to increase the fluid pressure on the bellows chamber 46. Obviously, any convenient source of fluid under suitable pressure can be substituted for the pressure generating means shown.

While I have herein shown and described, by way of illustration, a specific embodiment of my invention, I wish it to be understood that modifications may be made without departing from the spirit of the invention, and that I intend

therefore to be limited only by the scope of the appended claims.

I claim as my invention:

1. In a fluid control valve: a casing having a ported passage therethrough provided with a valve seat; a closure member cooperable with said seat; means constantly biasing said closure member away from its seat; movable means normally in engagement with said closure member and adapted when in that position to exert a force on the closure member urging it toward its seat with a force greater than that of said biasing means; a fluid pressure motor interposed between portions of said closure member and said movable means and comprising a pair of opposed and relatively movable walls; means extending exterior of said casing for varying the pressure of the fluid in said motor; said motor upon an increase in fluid pressure therein exerting a force effective to hold said closure member on its seat and simultaneously to move said movable means to a position wherein it is out of engagement with said closure member; and condition responsive means for retaining said movable means in its moved position so that the force exerted thereby on said closure member is removed; said motor upon subsequent decrease of fluid pressure therein being ineffective to exert said force holding the closure member on its seat so that the closure member is moved to open position under the force of said bias.

2. In a fluid control valve: a casing having a ported passage therethrough provided with a valve seat; a closure member cooperable with said seat; means constantly biasing said closure member away from its seat; movable means normally in engagement with said closure member and adapted when in that position to exert a force on the closure member urging it toward its seat with a force greater than that of said biasing means; a fluid pressure motor interposed between portions of said closure member and said movable means and comprising an expansible-contractible bellows; said bellows when expanded by increase of fluid pressure therein exerting a force effective to hold said closure member on its seat and simultaneously to move said movable means to a position wherein it is out of engagement with said closure member; condition responsive means for retaining said movable means in its moved position so that the force exerted thereby on the closure member is removed; said bellows when contracted due to subsequent decrease of fluid pressure therein being ineffective to exert said force holding the closure member on its seat; and manually operable means extending exterior of said casing for varying the fluid pressure in said bellows.

3. In a fluid control valve: a casing having a ported passage therethrough provided with a valve seat; a closure member cooperable with said seat; means constantly biasing said closure member away from its seat; a movable armature member normally in engagement with said closure member and adapted when in that position to exert a force on the closure member urging it toward its seat with a force greater than that of said biasing means; a fluid pressure motor interposed between portions of said members and comprising an expansible-contractible bellows; manually controllable means for varying the pressure in said bellows; said bellows when expanded by increase of fluid pressure therein exerting a force effective to hold said closure member on its seat and simultaneously to move

said armature member to a position wherein it is out of engagement with said closure member; and electromagnetic means for retaining said armature member in its moved position so that the force exerted thereby on the closure member is removed; said bellows when contracted due to subsequent decrease of fluid pressure therein being ineffective to exert the force holding said closure member on its seat.

4. In a fluid control valve: a casing having an inlet and an outlet separated by a ported partition provided with a valve seat; a closure member cooperable with said seat; means biasing said closure member away from its seat; a movable armature member normally in engagement with said closure member and adapted when in that position to exert a force on the closure member urging it toward its seat with a force greater than that of said biasing means; a fluid pressure motor interposed between said members and comprising a pair of opposed and relatively movable walls; manual means remote from said casing for varying the pressure of the fluid in said motor; fluid-conducting means interconnecting said manual means and said motor; a portion of said fluid-conducting means adjacent said motor being yieldable; said motor upon an increase in fluid pressure therein exerting a force effective to hold said closure member on its seat and simultaneously to move said armature to a position wherein it is out of engagement with said closure member; and electromagnetic means for retaining said armature in its moved position so that the force exerted thereby on the closure member is removed; said motor upon subsequent decrease of fluid pressure therein being ineffective to exert the force holding the closure member on its seat.

5. In a fluid control valve: a casing having an inlet and an outlet separated by a ported partition provided with a valve seat; a closure member cooperable with said seat; means biasing said closure member away from its seat; an armature member movable toward and away from said closure member; means urging said armature member toward said closure member with a force greater than that of said closure-member biasing means; means interposed between portions of said members and limiting their movement toward one another; said movement-limiting means being normally in a position engaging both of said members and when in this position adapted to transmit said armature-urging force to said closure member to urge the same toward its seat; a fluid pressure motor comprising means forming an expansible-contractible fluid chamber interposed between portions of said members; manually operable means remote from said casing for varying the fluid pressure in said chamber; fluid conducting means interconnecting said manually operable means and said motor comprising a yieldable section adjacent said chamber; said motor upon an increase in fluid pressure in said chamber exerting a force effective to hold said closure member on its seat and simultaneously to move said armature member to a position wherein said movement-limiting means no longer engages both of said members; and electromagnetic means for retaining said armature in its moved position so that the force transmitted therefrom to said closure member is removed; said motor upon subsequent decrease of fluid pressure in said chamber being ineffective to exert the force holding said closure member on its seat.

EUGENE PAILLE.
